METHOD AND MEANS FOR JOINING INDIVIDUAL WIRES IN TWO ROPES TO MAKE A SINGLE ROPE

Henry Allyn Wood, Berkeley, Calif.

Application May 15, 1934, Serial No. 725,777

9 Claims. (Cl. 117—6)

My invention relates to improvements in a method and means for joining individual wires in two individual strands to make a single strand, and to form the united strands into a rope, and it consists of the combinations, constructions and arrangements hereinafter described and claimed.

In the past it has been customary to join two ropes by splicing, which consists of unraveling a strand from one rope, and taking a strand from the other rope and winding it into the groove formed by the removed strand in the first rope. The same operation is carried out for the other strands and the result is two ropes which are spliced together.

In the present case the machine is so arranged that the individual strands of the two ropes are untwisted and then the wires in the strands of the two ropes are slightly opened and the individual wires in each strand are joined by welding, brazing, or other suitable means, to the symmetrically placed wire in the corresponding strand of the other rope, and a means is provided for then retwisting the strands together again, thus forming a continuous length of rope. I, therefore, wish it to be clearly understood that I am not contemplating the mere splicing of two ropes together, but that I am actually joining individual wires in separate strands of two ropes into continuous wires, these continuous wires forming continuous strands that connect the two ropes together. The machine winds the joined strands into a rope.

I make use of the machine shown in my co-pending application Serial No. 686,473, filed August 23, 1933 entitled "Method of and means for altering a steel rope." With this machine I am not only enabled to join two ropes together but I can substitute one or more new parts of a rope for a worn part in either of the ropes being joined.

Other objects and advantages will appear in the following specification, and the novel features of the device will be particularly pointed out in the appended claims.

My invention is illustrated in the accompanying drawings forming a part of this application, in which

Figure 1 is a schematic view of the machine showing one of the ropes carried by the machine;

Figure 2 shows the untwisting die in the machine;

Figure 3 is a section along the line 3—3 of Figure 1;

Figure 4 illustrates the joining of two ropes in which an end of each rope is fed into an end of the machine;

Figure 5 illustrates the joining of two ropes and the substitution of a new part for an old one; and

Figure 6 illustrates the joining of the wires in a rope strand.

In carrying out my invention I provide a cage indicated generally at 1, and this cage has elongated members or rods 2 connected to rings 3 and the entire cage may be revolved by means of a bevel gear 4, which in turn is operatively connected to a driving bevel gear not shown.

Within the cage I mount bobbin-carrying frames 5, and these are preferably supported along the axis of the cage so that the bobbins will remain in a horizontal position during the rotation 15 of the cage. Figure 1 illustrates the joining of a rope 6 carried by the frame 5 with a rope 7 entering through the retwisting die 8.

The rope 6 is mounted on a bobbin 9 that in turn is rotatably carried by the frame or cradle 20 5. The rope is passed through an untwisting die 10 and the strands 11 are led along the rods 2 of the cage and are slidably secured to the rods by idler pulleys 12. The rope core 13 is led through a centrally disposed sleeve 14, and then is guided 25 over to one of the rods 2 by means of an idler pulley 15.

The rope 7 which is to be joined to the rope 6 is passed through the die 8 and the strands 16 are guided through pulleys 17 and the strands are in 30 alignment with the strands 11 of the rope 6. The core 18 of the rope 7 is passed over a guide pulley 19, and this core 18 is in alignment with the core 13 of the rope 6.

The particular manner of joining the strands 35 11 and 16 or the cores 13 and 18 together, is shown in Figure 6. In this figure I illustrate the strand 11 as being composed of a number of wires 20, and I further show the strand 16 as being composed of a number of wires 21. The place of joining the strand 11 with the strand 16 is indicated by the line 22. Certain of the wires 21 in the strand 16 are unwound from their position in the strand, and are severed at a distance from the end 22 of the strand, such as at the line 23. Certain of the corresponding wires 20 of the strand 11 are threaded into the grooves formed by the removed wires in the strand 16, and are joined to the wires 21 by welding at the line 23. The same operation is repeated in the strand 11, that is, certain of the wires 20 are untwisted from the strand and are cut off at the line 24, and corresponding wires 21 in the strand 16 are threaded into the grooves in the strand 11 provided by the removal of certain of the wires 20. In this way the wires 50 55

21 extend into the strand 11 and are joined by welding at 24 to the wires 20. The result is a continuous strand in which all of the wires are welded together. Such an operation is not to be known as the splicing of two strands together, but is to be known as an actual joining of the two strands.

All of the other strands of the rope 6 are connected to the corresponding strands in the rope 7, as indicated at A, and in like manner the core 13 is connected to the core 18, as shown at B. After the joining has been made the cage is revolved on its supporting rollers 25, see Figure 3, and the rope 6 will be fed from the bobbin or 15 spool 9 and will issue from the die 8 as a continuous joined section of the rope 7. After the rope 6 has been entirely fed from the spool 9, and has issued from the die 8, the resulting rope will be the combination of the two ropes 6 and 7, and it will 20 be impossible to note where the joining of the two has actually been effected.

In order not to have the joining of the two ropes take place at one point in the rope, it may be desirable to join two corresponding strands of 25 the two ropes at one point, and then join two other corresponding strands of the same two ropes at a point some distance from the first one. In this way all of the joining of the strands will not be at one point in the rope. Figures 1 and 4 illustrate this.

I have described how two ropes can be joined together where one of the ropes is mounted in the machine and upon a bobbin 9. In Figure 4 I illustrate how two ropes may be joined together in which the rope 6 is fed into one end of the machine and the rope 7 is fed into the opposite end of the machine. The rope 6 feeds from a spool not shown and passes through a hollow shaft 26, and then through an untwisting die 27 similar to the die 10. The rope 7 in Figure 4 is led through the die 8 and the strands 16 and the core 18 are untwisted and are connected to the strands 11, and the core 13 of the rope 6 in the manner already described. The operation of this machine is identical to that shown in Figure 1, the only difference being that the rope 6 is fed from a spool disposed exteriorly of the machine.

In Figure 2 I have shown in section the die 27 and have illustrated how the die is operatively connected to the associate parts. A standard 28 supports the hollow shaft 26 and the rope 6 is fed through the shaft. A sleeve 29 is rotatably mounted on the shaft 26 and carries an end 30 of the cage 1. The bevel gear 4 is connected to the end 30 so that a rotation of this gear will rotate the cage.

The die 27 comprises a casing which houses two semi-cylindrical elements 31 and these elements are held against the wire rope 6 by screws 32. Figure 2 also illustrates how the strands 11 lead from an opening 33 in the die casing, and are passed around the idlers 12. The idler pulleys 12 are adjustable on the rods 2 by sleeves 34 which are held in adjusted position by screws 35.

It may be desirable not only to join two ropes together, but to substitute a new part for an old part of one of the ropes. I show the means for doing this in Figure 5, and it will be noted in this figure that the rope 6 is fed in at the entrance end of the machine in the same manner as illustrated in Figure 4. The strands 11 are untwisted from the rope and run along parallel with the rods 2 of the cage 1. The core 13 passes through the sleeve 14 and then the core is led over to one 75 of the rods 2. The rope 7 is entered in the exit

end of the machine and is passed through the die 8, and then the strands 16 are untwisted from the rope. Should it be desired to substitute a new core for the core 13, and a new strand for one of the strands 11, it is merely necessary to wind the core 13 on a take-up bobbin 36, which in turn is rotatably mounted in a cradle 37. While the core 13 is being wound on the bobbin 36, a new core 38, which has been connected to the core 18, is fed from the bobbin 39. The strand 11 which 10 is to be discarded is passed through a central sleeve 40 and is wound upon a take-up bobbin 41, while a new strand 42, which has been connected to one of the strands 16, is fed from a bobbin 43 as needed. 15

The particular arrangement of the take-up and feed bobbins is shown in detail in Figure 7 in my copending application, and need not be shown in this case. It is sufficient to say that the old strand or core is fed from side to side of the take-up bobbin, and the new strand is fed from the feed bobbin as it is needed. Sufficient braking force is applied to the feed bobbin to prevent it from over running, and to cause a certain amount of tension to be placed on the new strand or core as it 25 is being fed into the rope. It will be seen from the description of Figure 5 that the rope will be joined to the rope 6 and at the same time new parts will have been added. Any means for pulling the rope through the device may be used, such 30 as a power driven take-up reel 44 shown in Figure 5.

While I have shown only the preferred form of my invention, it should be understood that various changes or modifications may be made 35 within the scope of the appended claims without departing from the spirit of the invention.

I claim:

1. A device for joining two ropes together comprising a cage rotatable about its axis, means for 40 rotating the cage, a rope untwisting die disposed at one end and receiving one of the ropes, a rope retwisting die disposed at the other end, and receiving the other rope, means for slidably supporting the strands of both ropes along the sides 45 of the cage, the strands in each rope being separated from the other strands in the same rope, but being in alignment with the strands of the other rope, whereby the strands of both ropes may be joined, and means for pulling the joined 50 ropes through the machine.

2. A device for joining two ropes together comprising a cage rotatable about its axis, means for 55 rotating the cage, a rope carrying reel supported by the cage, a rope untwisting die receiving the rope from the reel, a retwisting die receiving a second rope, the strands from the ropes being separated, means for slidably supporting the strands along the sides of the cage so that the strands of one rope will be in alignment with the 60 strands of the other rope, whereby the strands of the two ropes may be joined, and means for pulling the second rope from the machine and with it the first rope, the two ropes being joined and twisted into one continuous whole. 65

3. A device for joining two ropes together comprising a cage rotatable about its axis, means for 70 rotating the cage, an untwisting die disposed at one end of the cage for receiving a rope and a retwisting die disposed at the other end and receiving a second rope, means for slidably supporting the strands so that the strands of one rope will be in alignment with the strands of the other rope, whereby certain strands may be joined together, means for withdrawing certain 75

parts of the first rope and for substituting similar parts in the completed rope, and means for drawing the second rope from the machine and with it the first rope with the substituted parts 5 for providing one entire rope.

4. A device for joining two ropes with cores comprising a cage rotatable on its axis, means for rotating the cage, an untwisting die carried by the cage and receiving a rope, a retwisting die 10 carried by the cage and receiving a second rope, means for separating the strands of each rope from each other and from the core and for aligning the strands and core of one rope with the corresponding strands and core of the other, 15 whereby the strands and core may be joined, and means for withdrawing one of the ropes from the cage and with it the other rope, the other rope being untwisted and retwisted as it passes through the cage, whereby a continuous 20 rope is provided equal to the two lengths of the original ropes.

5. A device for joining two ropes with cores comprising a cage rotatable on its longitudinal axis, means for rotating the cage, an untwisting die receiving a rope, a retwisting die receiving a second rope, means for separating the strands of each rope from each other and from the core and for aligning the strands of one rope with the corresponding strands of the other, whereby the 30 strands may be joined, means for withdrawing the core of the first rope as it is freed from the rope, means for substituting a new core for the withdrawn one, said new core being joined to the core of the second rope, and means for pulling 35 the second rope from the cage and with it the other rope and new core, whereby a continuous rope is formed of the two ropes with a substituted core for the portion of the rope formerly constituting the first rope.

6. A device for joining two ropes with cores comprising a cage, means for rotating the cage, an untwisting die for receiving a rope, a retwisting die for receiving a second rope, means for separating the strands of both ropes from each other and from the core and for aligning certain strands and the core of one rope with corresponding strands and the core of the other rope, means for withdrawing one strand from the 45 first rope and substituting a new strand, and means for pulling the second rope from the cage 50

and with it the first rope with the substituted strand, whereby a continuous rope is formed of the two ropes with a substituted strand for the portion of rope formerly constituting the first rope. 5

7. The method of joining two ropes which consists in separating the strands of each rope, aligning the strands of one rope with those of the other, unlaying certain wires in each strand of both ropes and winding into the groove provided thereby, the corresponding wire of the aligned strand, whereby all of the strands will be connected to their aligned strands, and finally in progressively unwinding the strands of one of the ropes from the place of joining, and 15 in again winding the strands of the same rope for forming one continuous rope made up from the two joined ropes.

8. The method of joining two ropes which consists in separating the strands of each rope, 20 aligning the strands of one rope with those of the other, unlaying certain wires in each strand of both ropes and winding into the groove provided thereby, the corresponding wire of the aligned strand welding the abutting ends of the 25 wires together, whereby all of the strands will be connected to their aligned strands, and finally in progressively unwinding the strands of one of the ropes from the place of joining and in again winding the strands of the same rope for forming 30 one continuous rope made up from the two joined ropes.

9. The method of joining two ropes which consists in separating the strands of each rope, aligning the strands of one rope with those of the other, cutting the aligned strands so that the place of joining of any two of the strands will be removed from the place of joining of all the other pairs of strands, unlaying certain wires in 35 each aligned pair of strands and winding into the groove provided thereby the corresponding wire of the aligned strand, welding the abutting ends of the wires after the winding process, and finally in progressively unwinding the strands of one of the ropes from the place of joining and in 40 again winding the strands of the same rope for forming one continuous rope made up from the two joined ropes. 45

HENRY ALLYN WOOD.
